CHARLES WHITING BAKER, OF MONTCLAIR, NEW JERSEY.

VALVE SYSTEM FOR INTERNAL-COMBUSTION ENGINES.

1,116,364.

Specification of Letters Patent.

Patented Nov. 10, 1914.

Original application filed March 20, 1912, Serial No. 685,045. Divided and this application filed July 10, 1912. Serial No. 708,574.

To all whom it may concern:

Be it known that I, CHARLES WHITING BAKER, a citizen of the United States, residing at Montclair, in the county of Essex and State of New Jersey, have invented certain new and useful Improvements in Valve Systems for Internal-Combustion Engines, of which the following is a specification.

The present application is a division of 10 an application filed by me March 20, 1912, Serial No. 685,045.

In internal combustion engines as ordinarily constructed, it is customary to use 15 puppet valves to control the inlet and exhaust ports and to place these valves in the cylinder heads. In engines of the two-stroke cycle type, however, the exhaust ports are placed in the barrel of the cylinder, and 20 opened and closed by the movement of the piston. The inlet ports may also be so placed and so governed; but it is then necessary to introduce a deflecting flange on the 25 piston to direct the entering air toward the top of the cylinder and scavenge out the burned gases.

It is the object of my invention to provide a valve system for internal combustion engines which shall not require the placing of any valves in the cylinder head, nor the formation of any deflecting flange on the piston, thereby enabling the cylinder head and piston to be made of symmetrical and dome shaped form so as to furnish maximum strength. I further avoid the use of puppet 35 valves and provide large and direct passages for the entry of the scavenging air, by using a multi-ported slide valve to control the inlet ports; and by providing means to give this valve a variable time of closure, according 40 to the load on the engine, I am enabled to expand the working fluid to low pressure before release, and thereby produce an internal combustion engine, which like the steam engine, will have its highest efficiency 45 at partial loads.

My invention is illustrated in the accompanying drawings in which—

Figure 1 is a vertical section through the cylinder of a two-stroke cycle engine embodying my improvements; Fig. 2, a horizontal section on the plane of the line 2—2

of Fig. 1; and Fig. 3 a side elevation of part of the valve shaft carrying a series of cams.

Similar reference numerals indicate similar parts in the several views.

Referring to the drawings, the piston 1 is driven downward by the pressure produced by the burning of a charge of oil sprayed through the pipe 2 into the combustion chamber formed between the piston 1 and the cylinder head 3. When the piston 1 travels far enough to uncover the ports 4, the burned gases behind the piston escape into the exhaust pipe 4'. As soon as the pressure behind the piston is reduced to atmospheric, which takes place almost instantaneously, the multi-port slide valve 5 is quickly opened and allows fresh air under the low pressure necessary for scavenging, to rush from the pipe 6 to which it is supplied by any suitable means, through the inclined passages 7 which direct it toward the top of the cylinder, thereby driving the remaining burned gases from the previous stroke, out through the exhaust ports 4. This action continues until the piston reaches the end of its travel and returns to cover the exhaust ports 4, when the inlet valve 5 also closes and compression begins.

It is one of the objects of my invention to reduce the necessary pressure for the scavenging air, and this I do by providing a large area for the passage of the entering air. Referring to Fig. 2 it will be seen that the slide valve 5 has a width greater than its height, so that when the valve is opened, a large area is available for the direct flow of the air to the cylinder. Further, the valve being of the multi-ported type, having bridges 8 between its ports adapted to cover ports 9 in the seat on which the valve moves, only a very slight movement is necessary to completely open or close the valve, and the prompt opening and closing necessary for effective scavenging can be easily obtained. At the time this valve 5 is opened and closed it is under no pressure from the cylinder, and the maximum pressure against it at any time is much less than that on valves governing ports in the combustion space, since the piston 1 covers the inlet ports 10 during all those parts of the cycle

where high pressure occurs. The valve 5 is cooled by the fresh air passing through it at each revolution, and is protected from the hot gases in the cylinder during the expansion stroke by the cool air pocketed in the inlet passage 7 beyond the valve.

I prefer to make the seat on which the valve 5 moves as part of the end section of the scavenging air supply pipe 6, so that it can readily be removed from the cylinder.

My improved valve system above described also furnishes means whereby the full economy of the engine may be materially increased at partial loads. In the present operation of internal combustion engines of the Diesel type, the amount of oil sprayed into the cylinder is regulated by the governor according to the load, but the piston compresses a cylinder full of air at each compression stroke no matter what the load. In some types of gas and gasoline engines operating on the four-stroke cycle, the charge of gas and air drawn in is throttled at partial loads, and while this effects the desired graduation in amount of working fluid, it wastes power since the piston on the suction stroke is working against a partial vacuum.

My improved valve system, here shown, makes possible the graduation of the amount of air as well as the amount of fuel, in the following manner: When the engine is operating at partial loads, the closing of the inlet valve 5 is delayed and the piston 1, on its return stroke, pushes part of the cylinder full of air back into the supply pipe 6. Compression in the cylinder, therefore, does not begin until valve 5 closes or until the inlet ports 10 are covered by the piston 1. If the piston 1 compresses only half a cylinder full of air into the clearance space, the negative work of compression will be approximately only one-fourth as great (since only half as much air is compressed and the pressure attained is only about half as much) as if a whole cylinder full were compressed. On the other hand, the temperature attained in combustion will be higher, since an amount of oil suitable for half loads has only half as much air to heat as if a full cylinder of air had been drawn in and compressed. At the completion of the stroke, moreover, the gases will be expanded to lower pressure and temperature, than would have been the case had a whole cylinder full of air been compressed. Inasmuch, therefore, as the initial temperature is higher and the final temperature is less, the proportion of heat converted into power on the working stroke will be increased. In order to operate in this manner under most favorable conditions, however, it is preferable to use heat insulating materials on the cylinder head and piston, as shown in Fig. 1 and described in my application No.

685,045. These operate first to retain the heat in the expanding gases, which is especially advantageous because the large ratio of expansion effectively utilizes this heat, and second to effect ignition of the charge after the insulating surfaces are heated at the low compression pressures produced when only part of a cylinder full of air is compressed.

The valve gear for operating the valve 5 and opening and closing it at the proper times may be made in a variety of forms to suit different conditions.

Fig. 3, shows a suitable means for varying the time of closing of the valve. The valve shaft 11 carries two or more cams 12 which operate a lever 13 connected to the valve 5. The curves of these several cams are such that each of them operates to open the valve at the same point of the revolution; but the time during which the valve is held open is different with the different cams. By sliding the valve shaft 11 lengthwise in its bearings, any one of the cams may be brought into action, and the time of closing of the valve 5 will be thus varied according to which cam controls it.

What I claim is:

1. A two-stroke cycle internal combustion engine having in the barrel of its cylinder a plurality of inlet ports with passages inclined toward the head of the cylinder leading to said ports, and a multi-ported valve for governing said passages.

2. In a two-stroke cycle internal combustion engine having inlet ports in the barrel of its cylinder and inclined passages leading thereto, a rectangular valve governing said passages and having a plurality of narrow parallel ports with bridges between, and a seat for said valve having corresponding ports with intermediate bridges adapted to register with those of the valve.

3. In a two-stroke cycle internal combustion engine having inlet ports in the barrel of its cylinder and inclined passages leading thereto, a multi-ported valve governing said passages and a multi-ported seat on which said valve rests, said seat forming part of the inlet pipe removably attached to the cylinder barrel.

4. In an internal combustion engine, a cylinder having in the barrel thereof a plurality of air inlet ports and inclined passages leading to said ports to direct the entering air toward the cylinder head, an air inlet pipe communicating with said passages, and a multi-ported valve in an enlargement of said pipe as and for the purpose described.

5. A two-stroke cycle internal combustion engine comprising a cylinder having in the wall thereof a plurality of inlet ports and inclined passages leading to said ports to direct the entering air toward the cylinder

head, an air inlet pipe, and a multi-ported slide valve for governing the admission of air, said ports being so located that they are covered by the piston during those parts 5 of the cycle where high pressure occurs.

6. A two-stroke cycle internal combustion engine comprising a cylinder having in the wall thereof a plurality of air inlet ports, a plurality of exhaust ports below the inlet 10 ports, a trunk piston adapted to uncover the exhaust ports near the end of its expansion stroke, a valve governing the inlet ports,

and means to delay the closing of said valve at partial loads, whereby compression in the cylinder will not begin until said valve 15 closes or until the inlet ports are covered by the piston.

In testimony whereof I have hereunto signed my name in the presence of two subscribing witnesses.

CHARLES WHITING BAKER.
